UNITED STATES PATENT OFFICE.

HILAND R. FARNSWORTH AND THOMAS H. SAVERY, JR., OF SANDUSKY, OHIO.

SCREEN-PLATE CLEANER.

1,167,808.

Specification of Letters Patent.

Patented Jan. 11, 1916.

Application filed September 30, 1915. Serial No. 53,242.

To all whom it may concern:

Be it known that we, HILAND R. FARN-
WORTH and THOMAS H. SAVERY, Jr., citizens
of the United States of America, residing
5 in the city of Sandusky, county of Erie, and
State of Ohio, have invented certain new
and useful Improvements in Screen-Plate
Cleaners, of which the following is a speci-
fication.

10 This invention relates to improvements in
devices for cleaning the screens which are
used in the manufacture of paper. Such
screens are shown in a patent granted to
H. R. and W. R. Farnsworth on March 3,
15 1903, No. 721,875. It is a well known fact
that the openings in screen plates like the
one referred to often become clogged up
with the paper pulp or some other foreign
substance or material, preventing the wa-
20 ter contained in the pulp from freely escap-
ing through the openings or screen plate
slots prior to its passage onto the paper
making machine. Our invention is designed
25 to provide a device for readily removing
the paper pulp, foreign or objectionable
matter or material from the slots or open-
ings of the screening surface. Broadly, it
comprises a nozzle or suction tool so de-
30 signed and of such shape or form that it
may be passed over the screening surface,
(whether it be round, angular, or flat) on
the same side or surface which receives the
stock or pulp, or onto which the stock flows
35 in passing through the plates or screening
surface. It is, of course, understood that
the tool is not limited in its use to a screen
having a flat surface as it may be used on
screen plates that are round. Such a de-
40 vice is also useful in cleaning Fourdrinier
wires, cylinder faces, suction rolls, shower
pipes, etc., of the paper making machine,
if desired.

Referring to the drawings, which form a
part of the specification Figure 1 is a trans-
45 verse sectional view on the line 1—1 of Fig.
2, clearly showing the construction of the
tool; Fig. 2 is a longitudinal sectional view
on the broken line 2—2 of Fig. 1, showing
the manner of inserting the removable block
50 or foot piece.

Referring to the drawings in detail—1
designates the casing member having the
depending sides 2, and the centrally lo-
cated threaded opening 3 in which the suc-
55 tion pipe 4 is located, the attachment being

made by means of the usual threaded con-
nection.

5 is a removable face piece or block pref-
erably formed of wood, or hard rubber, al-
though we do not limit ourselves to the use 60
of any particular substance or material.
This block is made so as to have a tight,
yet easily removable, fit within the casing
1. Its lower edge is made with an inclined
surface, as indicated at 6, which terminates 65
and coincides with the lower edge 7 of the
casing, as shown.

8 designates a longitudinal opening which
opens into an enlarged opening 9, the width
of which is substantially equal to the inside 70
diameter of the suction pipe.

The screen plate cleaners are used by con-
necting a suitable suction device to the pipe
4, as a vacuum pump or other suction or
vacuum creating device or means, by means 75
of a piping or hose connection. The device,
as stated above, is intended for use by simply
moving the cleaner over the slotted or per-
forated parts of the screen plates while
the screen is in operation, or otherwise. By 80
using the vacuum cleaner the circulation of
the stock and water through the screen
plates is reversed, and, by drawing or suck-
ing the water and pulp back through the
screen the fibers or dirt may be loosened and 85
the slots effectively cleaned.

It is to be understood that we do not con-
fine ourselves to any specific shape or form
of the removable piece 5, as other forms
90 may, if desired, be used, also we do not con-
fine ourselves to any specific use as the screen
plate cleaner may be employed for other
analogous or similar uses.

One of the advantages of our invention
in making the block removable from the 95
casing is that in case the lower surface be-
comes worn or irregular in shape so that
the suction is not perfect, it may be readily
removed and its lower edge straightened by
planing or grinding.

It is to be understood that the stock and
water which is drawn up by the screen plate
cleaner and the vacuum pump should, of
course, be returned to the main circulating
system, as may be desired.

What we claim is—

1. A vacuum screen plate cleaner com-
prising, in combination, a casing having de-
pending sides and an open recessed bottom
portion, a block removably fitted in the cas- 110

ing and formed with an elongated opening in its lower side, said opening leading to an enlarged elongated opening having flaring or inclined sides which extend outwardly 5 from the elongated opening, and a suction pipe connected to the casing to which a vacuum producing means may be connected, as described.

2. A vacuum screen plate cleaner comprising, in combination, a casing having depending sides and an open recessed bottom portion, a block removably fitted in the casing and formed with an elongated opening

in its lower side, said opening leading to an enlarged elongated opening having flaring or inclined sides which extend outwardly 15 from the elongated opening, and a suction pipe connected to the casing to which a vacuum producing means may be connected, said block having its lower surface formed 20 with inclined oppositely extending surfaces which terminate at the lower inner edge or border of the opening formed by the depending sides of the casing.

H. R. FARNSWORTH.
THOMAS H. SAVERY, JR.
